W. H. NEIL,
RAZOR BLADE SHARPENER,
APPLICATION FILED FEB. 27, 1914.

1,112,827.

Patented Oct. 6, 1914.

UNITED STATES PATENT OFFICE.

WILLIAM H. NEIL, OF CINCINNATI, OHIO.

RAZOR-BLADE SHARPENER.

1,112,827.

Specification of Letters Patent.

Patented Oct. 6, 1914.

Application filed February 27, 1914. Serial No. 821,513.

To all whom it may concern:

Be it known that I, WILLIAM H. NEIL, a citizen of the United States, residing at Cincinnati, in the county of Hamilton and State of Ohio, have invented a certain new and useful Improvement in Razor-Blade Sharpeners, of which the following is a specification.

This invention relates to razor-blade sharpening devices and its object is to provide a pair of sharpening and smoothing or stropping rollers mounted in a rocker-frame which latter, in turn, is mounted in a suitably coupled pair of suspension-arms that carry at their lower ends a razor holding or gripping clamp in convenient position for the upwardly-disposed razor edge whose opposite sides are adapted to be alternately engaged by said rollers in the sharpening process, and a strap or strip of cotton-duck or cadet webbing or the like used in the rocker-frame to pass over said rollers in frictional-contact therewith and whereby the rollers are each rotated in reverse directions for proper contact with the edge of the blade at both sides thereof.

The details of the invention will be fully hereinafter described and then particularly pointed out in the claims.

30 In the accompanying sheet of drawings, Figure 1 is a side elevation, showing the device at rest and with the roller actuating web or strap partly broken off at its opposite ends; Fig. 2, a vertical transverse section taken axially of Fig. 1; Fig. 3, a vertical longitudinal section, showing the device with its rocker-frame tilted so as to bring one of the rollers in contact with one side of the edge of the razor-blade; Fig. 4, a 35 detail perspective view of the suspension-frame detached from the roller rocker-frame and razor clamping or gripping device; Fig. 5, an end elevation of the preferred form of razor clamp, showing a combination of a pair of clamps adapted to hold or grip various forms of safety-razor blades and of blades used for other purposes; and Fig. 6, an end elevation of the outer or main clamp seen in Fig. 5.

50 1 indicates each one of a pair of corresponding vertical arms or bars having a transverse suspending or swinging bail 2 to connect their upper ends and a transverse horizontal bar or ligament 3 integrally-con-

necting their lower ends as best seen in Fig. 55 4. The lower bar 3 is vertically notched at 4, and a transverse bar or pin 5 is provided near the upper end of the arms 1, with its outer ends duly shouldered and riveted or headed for properly fastening the arms 1 in 60 spaced relation. The outer ends of the bail 2 are similarly shouldered and riveted, but the arms 1 are free to turn or swivel thereon, however, when the device is in use and said bail is also thereby adapted to be folded inwardly when the device is not in use, especially for limited or close packing space, as best seen in Figs. 2 and 4. The transverse bar or pin 5 preferably carries a friction-roller 6 for the purpose herein- 70 after more fully referred to.

7 indicates each one of a pair of corresponding horizontal side-members mounted on the transverse pin 5 and forming a rocker-frame and carrying a pair of rollers 8 75 and 9 that are, in turn, mounted on transverse pins 10 and 11 that are horizontally-aligned in the said side-members 7 and composed of wooden cores with thin leather or buff covers 12 that are especially adapted to 80 receive and hold the honing and stropping material such as crocus, rouge or similar paste ordinarily used in sharpening and polishing metals. The wooden core of each roller has a central lining or bush 13 85 through which the pins 10 and 11 pass and provide against undue wear, as well as to maintain a uniform distance between the faces of the rollers for the better operation of the device on the razor-blades to be 90 sharpened.

A razor-blade carrier-clamp is adjustably and detachably mounted on the lower transverse bar or ligament 3 of the vertical arms 1 that form a suspension-frame for the roller carrying and rocker frame. This razor-clamp is preferably composed of a main or outer pair of open spring gripping-jaws 14 and an inner pair of spring gripping-jaws 15, the inner coupled end of the jaws 14 being shaped to conform to and embrace a broad-backed blade and the outer ends being bent and tapered or flared inwardly to embrace the outer thin portion or edge of the blade and, also, to compress the flat 100 members of the inner jaws 15 on a thin blade 15^a that is held or gripped therein, the latter as shown in Fig. 3. The inner coupled

end of the main jaws 14 is also adapted to tightly embrace the bulged sides of the inner end of the jaws or clamp 15, as best seen in both Figs. 3 and 5. It is obvious that any 5 of the various shapes of razor-blades in use are adapted to be held between the two clamp-members 14 and 15, the outer one 15 being adapted to be used alone or both clamps 14 and 15 being adapted to be used 10 together as circumstances or conditions may require.

A coupling-bolt 16 is provided for the two clamp-members 14 and 15 and a thumb-screw 17 used at one end to engage the upwardly-notched portion 4 of the transverse bar or ligament 3 for ready adjustable and detachable fastening in place. The razor-blade can thus be accurately positioned and held in the device for presenting its entire 20 edge to be sharpened to the faces of the rollers in proper alinement for producing the desired result.

18 indicates a leather or canvas-duck strap or strip of a width slightly less than the 25 length of the rollers 8 and 9 and adapted to be drawn back and forth over the upper part of the periphery of each of said rollers, as best seen in Fig. 3, the intermediate portion of the strap engaging under the friction-roller 6 on the transverse pin 5, to reduce wear and facilitate the reciprocal movements of the strap and to bring the strap slightly below the upper plane of the two 30 rollers for bettering the contact on the rollers to actuate them first in one direction and then in a reverse direction to suit the position of the razor-blade that is in contact with one or the other roller as a result of a downward pull on either end of the strap, 35 the end to the left in Fig. 3 having been drawn downward by the operator and rocking the roller carrying frame so that the roller 8 is in contact with one edge of the razor-blade during the passage of the strap 40 in a direction to the left in said view, as indicated by the adjacent arrow, and the rollers being always actuated or rotated away 45 from the edge of the blade in the sharpening process.

50 The roller frame can be readily rocked on the pin or shaft 5 to suit the position of the manipulating strap or web 18 at either end of its stroke, or the position of the upwardly-disposed edge of the razor-blade in 55 the operation of sharpening the latter on both sides of its cutting edge for the desired shaving condition.

I claim:—

60 1. In a razor sharpening device, a pair of suspension-arms having a cross-bar, a rocker-frame mounted in said arms, a pair of rollers having blade sharpening and smoothing surfaces and mounted to rotate in said rocker-frame, a strap or strip of webbing 65 or the like adapted to frictionally-engage

said cross-bar in the suspension-arms and, also, the sharpening and smoothing rollers carried by the said rocker-frame, and a blade-carrier mounted in said arms below the rollers and adapted to present the edge 70 of the blade to said rollers for the sharpening and smoothing operation.

2. A razor-blade sharpener comprising a pair of parallel corresponding side-members, a pair of aligned transverse bars or pins of 75 circular cross-section adapted to suitably space and connect said side-members, a pair of buff-covered rollers having a coating of sharpening-paste thereon and mounted on said transverse pins between the side-members, a single bar or pin extending transversely across the space between the side-members parallel to said pair of transverse bars or pins and slightly below the common level of the upper peripheries of the pair of 80 rollers and with its opposite ends extended somewhat beyond the outer faces of the said side-members, a suspension-frame composed of a pair of vertical arms having an upper transverse pivotal bail or swivel-bar and a 85 lower transverse connecting-ligament and adapted to pivotally-support between them the roller-containing side-members on the said single transverse bar or pin whose outer extended ends are duly headed or riveted, 90 a razor-blade holding-clamp adjustably and detachably mounted on the said lower connecting-ligament of the suspension-frame and adapted to present the edge of the blade 95 to the sharpening surfaces of the rollers, and a strap or short strip of webbing or the like 100 passing under the said single transverse bar or pin and over the peripheral surfaces of the two rollers to contact back and forth with the latter and rotate them in reverse 105 directions for alternate engagement with both sides of the sharp edge of the razor-blade.

3. A razor-blade sharpener comprising a pair of vertical arms or bars having a transverse swinging or suspending bail to connect their upper ends and a notched horizontal bar or ligament to connect their lower ends, 110 a transverse pin carrying a friction-roller and having its opposite ends in engagement 115 with the said vertical arms intermediate their said upper and lower ends, a pair of corresponding horizontal side-members having centrally-aligned holes therein that are adapted to engage said transverse pin and provide for a rocking-movement of the said side-members, a pair of buff-covered rollers 120 surfaced with a sharpening-paste and mounted on a pair of horizontally-aligned transverse pins in said side-members, a 125 razor-blade carrier-clamp adjustably and detachably mounted on the lower notched ligament of the vertical arms and provided with two sets of gripping-jaws one of which sets is removable from the other, and a reciprocating 130

cally movable or sliding strap or strip of webbing or the like passing under and in contact with the said friction-roller and, also, over and in contact with the sharpening-surfaces of the two rollers whereby the latter are rotated or driven in alternate directions first against one side of the sharp

edge of the blade and then against the other side of said edge in the process of putting said edge in condition for use.

WILLIAM H. NEIL.
